UNITED STATES PATENT OFFICE.

WILLIAM RODERICK BARCLAY AND WILFRID THOMAS MINETT, OF LEICESTER, ENGLAND, ASSIGNORS TO UNITED SHOE MACHINERY CORPORATION, OF PATERSON, NEW JERSEY, A CORPORATION OF NEW JERSEY.

SUPPORT.

Application filed June 20, 1924, Serial No. 721,193, and in Great Britain July 24, 1923.

This invention is concerned with supporting or positioning the work or a tool in operations on shoes or parts thereof, and particularly relates to the supporting of shoes when on their lasts by a projection, known as a last-pin or spindle, which enters an opening in the last. Shoes are commonly supported in this manner for many operations where pressure is to be applied. Among these operations may be given as examples, heel-attaching and sole-laying or leveling. Sometimes the last-engaging spindle is utilized to guide a driver for inserting a nail or other fastening to hold a heel temporarily upon a shoe, a hole being bored through the cone of the last for this purpose. This is as illustrated in British Patent No. 177,015, Haldinstein, March 23, 1922. In attaching heels in the manner indicated above, there is sometimes difficulty in securing the heel firmly, owing to its tendency to turn about the axis of the fastening. The removal of this difficulty is one of the objects of the invention, and for this purpose we provide a support having a last-engaging projection, in which a plurality of tools, as drivers, may operate together at opposite sides of the axis of said projection and parallel thereto to effect the insertion of a plurality of fastenings side by side in the heel. By the insertion of a plurality of such fastenings, the heel can be held against any twisting tendency without undue, if any, enlargement of the hole in the last, since the drivers and driver and fastening-guides may be of less diameter than when a single fastening is used.

When such a device is employed upon heel-attaching machines of the usual character, the fact that the last must be placed upon and removed from a last-entering spindle, which, to guide the fastening or fastenings, must be approximately of the full depth of the rear of the last, requires a clearance between the upper and lower work-engaging members of the machine, that is substantially greater than that needed when inside attaching is being performed without a last in the shoe. This clearance may be greater than the machine is designed to provide, and with the correction of this defect as one of its objects, this invention furnishes a support having upper and lower sections

pivoted together, the upper section carrying the last-engaging projection. This permits the last-entering spindle to be swung out to a point at which the operator has free access to it, for the purpose of applying and removing the lasted shoe.

One form of work-support or jack embodying our invention is illustrated in the accompanying drawing, in which—

Fig. 1 is a central, vertical section through the improved support, the parts being in work-receiving position;

Fig. 2 is a partial vertical section with the elements in nailing position; and

Fig. 3 is a horizontal section on the line 3—3 of Fig. 2.

This organization may be employed, for example, in such machines as those disclosed in United States Patent No. 1,195,134, Gouldbourn, Aug. 15, 1916, and No. 1,269,654, Standish, June 18, 1918. At 10 appears the top of a jack-base, having reciprocating within it a driver-actuating member 12. Mounted in the upper extremity of the base is the lower section 14 of the body-portion of the jack, and pivoted at 16 to this is the upper section 18 of the jack-body. Opposite surfaces 20, 20 upon the adjacent ends of these sections contact to hold said sections in normal axial alinement, this being the nail-driving relation. The pivotal connection permits the upper section to be swung outwardly, as indicated in Fig. 1 of the drawing, to an extent limited by contacting stop-surfaces 21 associated with the pivot, to a position convenient for the application of the work to the jack. Both sections are tubular, the upper being closed at the top by a head 22. Rising from this head is a projection 24, furnishing a spindle adapted to enter the pin-hole of a last. Through the spindle are a plurality of longitudinal passages, of which two are illustrated, these being parallel to the axis, at opposite sides thereof, and receiving operating tools, as drivers 26. The drivers are held by some such fastening device as a pin 27, passing through horizontal bores in them, within sockets formed in the end and at opposite sides of the axis of a plunger or carrier member 28 movable in the axial bore of the section 18. This connection of the drivers to the plunger is preferably such as to give some lateral play, to better allow the drivers

to a position convenient for the application of the work to the jack. Both sections are tubular, the upper being closed at the top by a head 22. Rising from this head is a projection 24, furnishing a spindle adapted to enter the pin-hole of a last. Through the spindle are a plurality of longitudinal passages, of which two are illustrated, these being parallel to the axis, at opposite sides thereof, and receiving operating tools, as drivers 26. The drivers are held by some such fastening device as a pin 27, passing through horizontal bores in them, within sockets formed in the end and at opposite sides of the axis of a plunger or carrier member 28 movable in the axial bore of the section 18. This connection of the drivers to the plunger is preferably such as to give some lateral play, to better allow the drivers

to aline themselves with the passages in the spindle. The bottom of the plunger 28 is divided at 30 to receive the pivotal connection of a link 32 articulated at its lower extremity to a divided portion of a plunger 34 movable in the bore of the jack-section 14. The upper pivot-pin of the link may be reduced at 36 and enter a groove 38 in the wall of the section 18, this preventing the plungers from rotating, maintaining the alinement of the drivers with the spindle-passages. The plunger 34 has a depending stem 40 passing through a contracted opening in the section 14 and contacting with the actuating member 12. The plungers and drivers are held yieldably in their depressed position, at which the upper ends of the drivers are below the tops of the spindle-passages, by a spring 42 surrounding the plunger 28 and the drivers, this spring abutting at one end against a shoulder upon the plunger, and at the opposite end against the inner side of the head 22.

In using the jack, the section 18 is swung forward to the position appearing in Fig. 1, at which it is clear of the abutment member which exerts pressure upon the heel to hold it in place for nailing. Nails are now supplied to the spindle-passages, their heads resting upon the upper extremities of the drivers, and a lasted shoe is placed upon the spindle, which enters the hole in the rear portion of the last, passing through this into proximity with the heel-seat, the crown of the last resting upon the upper surface of the head 22. The section 18, with the jacked shoe, is then returned to its vertical position, and the machine started, to cause the actuating member 12 to rise, this, by its contact with the stem 40, elevating the plunger 34, which, in turn, carries up the plunger 28 with the drivers, forcing the nails through the heel-seat of the shoe into the heel, to fix the latter in place.

Having described our invention, what we claim as new and desire to secure by Letters Patent of the United States is:

1. A jack comprising a body-portion, a spindle projecting from said body-portion and arranged to enter an opening in a last, the spindle having passages situated at opposite sides of and parallel to its axis, a carrier mounted to reciprocate in the body-portion, and drivers mounted upon the carrier at opposite sides of its axis and extending into the spindle-passages.

2. A support comprising a body-portion having lower and upper sections pivotally connected, the upper section being provided with a tubular projection arranged to enter

an opening in a last, and a tool movable in the projection.

3. A support comprising a body-portion having lower and upper sections pivotally connected, the upper section being provided with a tubular projection arranged to enter an opening in a last, co-operating plungers movable in the sections, a driver mounted upon the plunger in the upper section and extending into the projection, and means for actuating the plunger of the lower section.

4. A support comprising a body-portion having lower and upper sections pivotally connected, the upper section being provided with a tubular projection arranged to enter an opening in a last, co-operating plungers movable independently in the sections, drivers mounted upon the plunger in the upper section and extending into the projection, means for actuating the plunger of the lower section, and a connection between the plungers.

5. A support comprising a body-portion having lower and upper sections pivotally connected, co-operating plungers movable in the sections, a link connecting the plungers, a driver mounted upon the plunger in the upper section, means for actuating the plunger of the lower section, and a spring arranged to maintain the co-operation of the lower plunger with the actuating means.

6. The combination with a jack-base, of a body-portion of a jack fixed thereon, a jack-portion pivoted upon the body-portion and provided with a tubular projection arranged to enter an opening in a last, and a tool movable in the projection.

7. The combination with a jack-base, of a body-portion of a jack fixed thereon, a jack-portion pivoted upon the body-portion and provided with a tubular projection arranged to enter an opening in a last, a tool-carrier and a plunger respectively arranged for bodily movement in the jack-portions, and connections between the carrier and plunger.

8. The combination with a jack-base, of a body-portion of a jack fixed thereon, a jack-portion pivoted upon the body-portion and provided with a tubular projection arranged to enter an opening in a last, a tool-carrier and a plunger respectively arranged for bodily movement in the jack-portions, a link connecting the carrier and plunger, and a reciprocatory actuating member contacting with the plunger.

In testimony whereof we have signed our names to this specification.

WILLIAM RODERICK BARCLAY.
WILFRID THOMAS MINETT.
